UNITED STATES PATENT OFFICE.

THOMAS H. WRIGHT, OF LOS ANGELES, CALIFORNIA.

MONORAIL ENGINE.

Application filed November 2, 1923. Serial No. 672,279.

To all whom it may concern:

Be it known that I, THOMAS H. WRIGHT, a citizen of the United States, residing at Los Angeles, in the county of Los Angeles 5 and State of California, have invented new and useful Improvements in Monorail Engines, of which the following is a specification.

My invention relates to monorail engines 10 and has for its purpose the provision of a novel safety drive and braking mechanism.

An object of my invention is to render a monorail engine safe against accident due to breaking of the driving means while the 15 engine is located upon a grade track.

Another object is to provide a novel braking means which may be concurrently applied to the front and rear wheels of a monorail engine.

20 A still further object is to provide auxiliary braking means applicable to the monorail.

Other objects and advantages of my invention will be made manifest in the following specification and accompanying drawings, in which,

Fig. 1 is a side elevation of my improved monorail engine.

Fig. 2 is a bottom plan of the same.

30 Fig. 3 is a diagrammatic view of the service braking mechanism.

Fig. 4 is a vertical sectional view showing the auxiliary braking mechanism in non-braking position.

35 Fig. 5 is a sectional view taken on the line 5-5 of Fig. 4.

Fig. 6 is a sectional view taken on the line 6-6 of Fig. 5.

In the operation of monorail trains over 40 hilly terrain, I have discovered that the great strain of starting a train on a grade is liable to break one or both of the mechanisms provided for delivery of the motive power from the motor to the wheels. In order to overcome this, I have provided a double sprocket 15 upon each end of the driving axle 16 of the monorail motor M. In alignment with a gear of each of the double sprockets 15 and fixed to supporting 45 axles 17 are driven sprockets 18. Chains 19 connect the driven and drive sprockets thus aligned and transmit the motive force from the motor M to the main supporting axles 17 and thus to the grooved wheels 20 mounted thereon. As will be seen by reference to 50 Fig. 2, dual power transmitting means is

thus provided between the motor and each of the axles 17. With an engine provided with this mechanism one of the chains 19 might break and the axle 17 would still be 60 driven by a chain 19 upon the opposite side of the motor. The axles 17 are journaled in boxes 21 which are provided with adjusting links 22 for shifting the axles 17 longitudinally to tighten or relax the chains 19 as 65 desired.

For operating in the hills it is found necessary to provide my monorail engine with sand boxes 8 and sand dispensing pipes 23 from which the dispensing of sand in the 70 path of the wheels 20 is controlled by any suitable means (not shown).

Braking means for concurrently retarding the axles 17 is provided. This comprises brake drums 24 fixedly mounted upon 75 the axles 17, and contacted by shoes 25 carried by brake jaws 26 and 27 which are pivoted at 28 to the frame of the engine. Means for swinging the jaws 26 and 27 toward each other and bringing the shoes 25 80 in contact with the brake drum 24 for effecting braking action comprises a lever 29 fulcrumed at 30 in the bifurcated upper terminal portion of the jaw 26. At the opposite end of the lever 29 is pivotally attached an operating link 31 the other end of which is pivoted to the end of an arm 32 mounted upon an operating shaft 33. Pivotally mounted upon the lever 29 and medially from the ends thereof is a rod 34 90 which passes through a boss 35 formed upon the frame of the vehicle and a spring 36 and a collar 37 mounted pivotally in the upper terminal bifurcated end of the jaw 27. A nut 38 is turned down upon the threaded 95 end of the rod 34 against the collar 37 so that when the operating shaft 33 is rotated so as to draw the link 31 away from the brake, jaws 27 and 26 will be rocked toward each other thereby effecting a braking action.

As will be seen in Fig. 3, rotation of the operating shaft 33 causes braking action concurrently on both the front and rear brake drums 24. As will be understood, this is a very desirable feature in a monorail engine where there are but two wheels for effecting driving and braking action for the entire train of cars. A hand lever 39 is mounted upon the operating shaft 33 and provided with a ratchet keeper 40 for operation and maintaining the brakes in braking relation with the drums 24.

An auxiliary or modified form of braking means which I have found very successful upon my monorail engines is illustrated in Figs. 4 to 6. In this form of brake a jack screw 41 threadedly engages a cross piece 42 connecting the sides of a frame 43. The screw 41 is provided at its upper extremity with a wheel 44 for manual rotation of the same. As will be clearly seen in Fig. 4, the lower end of the jack screw 41 is turned down to provide a shoulder 45 and a threaded pin 46. This pin fits closely an opening in a bracket 47 so that the shoulder 45 bears against said bracket. The bracket 45 is mounted upon a brake shoe 48 which may be lowered in contact with the rail R by rotation of the hand wheel 44. A nut 49 is turned onto the jack screw 41 and forms a shoulder to limit the downward movement of the jack screw 41. This serves to keep the operator from screwing the jack screw 41 down to such an extent that the wheel flanges would jump the rail. Braces 50 are provided pivotally secured to the frame 43 at 51 and rigidly secured to the brake shoe 48 at their opposite ends. These braces serve to transmit to the frame 43 retarding tendency of the brake shoe when pressed against the rail. When it is desired to life the brake shoe 48 from the rail, the jack screw 41 is rotated so that it will be screwed upward through the cross bar 42. As the jack screw rises the nuts 52 on the pin 46 bear against the underside

of the bracket 47 lifting the brake shoe 48 from engagement with the rail R. The bottom surface of the brake shoe 48 is provided with down turned edges 53 which prevent any possibility of the shoe leaving the rail when pressed into engagement therewith.

It will thus be seen that I have invented a very effective braking means particularly adapted for use on vehicles of the monorail type. While some of the monorail engines which I now have in operation are merely fitted for the brake illustrated in Fig. 3, for the more hilly regions I find that additional braking surface than that supplied by the two supporting wheels is necessary in which case I am adding to the engine equipment the brake illustrated in Figs. 4 to 6.

What I claim is:

In a monorail car construction having a frame with axles at opposite ends mounted therein, central wheels on said axles, the combination of a centrally positioned engine having a driving axle, a pair of sprockets on each end of the driving axle, a pair of sprockets on each of the supporting axles between the wheels and the bearings, and sprocket chains leading in opposite directions from the sprockets on the driving axle, said chains driving the sprockets on the supporting wheels.

In testimony whereof I have signed my name to this specification.

THOMAS H. WRIGHT.
